UNITED STATES PATENT OFFICE

WILLIAM H. BAYNARD, OF BROOKLINE, MASSACHUSETTS, ASSIGNOR TO HARRY H. BECKWITH, OF BROOKLINE, MASSACHUSETTS

SHOE-STIFFENER-ASSEMBLING PRESS

Application filed December 3, 1924. Serial No. 753,641.

This invention relates to presses for facilitating the fixing of shoe stiffeners in shoe uppers prior to the assembly of the shoes on the lasts in the manner fully described and 5 claimed in my application for patent Serial No. 619,555, filed February 17, 1923, for method of assembling stiffeners in shoe uppers and the article produced thereby. According to this method, a shoe stiffener comprising a 10 fibrous base saturated with thermoplastic material and skived along its rear margin is subjected along the skived portion to heat, as by placing it on a hot plate, so as to cause a local melting and exudation or "frying out" 15 of the thermoplastic. While this "fried out" material is still hot and sticky the stiffener is placed in position on the shoe upper so that the sticky saturant may partially penetrate the adjacent portion thereof, either the lining, the doubler or the leather, and the parts 20 are pressed firmly together. The exuded thermoplastic material on being allowed to harden securely fixes the stiffener in position.

The present invention is concerned with 25 a machine for pressing the parts together. To facilitate the assembly of the stiffener and the upper, the machine is provided with a stationary work table having a flat top on which the parts may be placed in assembled condition. Back of this table is an upper jaw member fixed at a height which permits the upper with the stiffener to be moved backwardly thereunder by the operator. A lower jaw then moves upwardly toward the upper 30 jaw so that the upper and stiffener are pressed firmly together. The operator may then let go of the parts and proceed to assemble another upper and stiffener on the work table in the same manner. After the pressure has 35 been exerted on the assembled parts for the desired short time, the lower jaw of the press descends and tips to permit the upper with the stiffener fixed thereto to drop out of the machine, there being, if desired, means 40 to positively detach the parts from the lower face of the fixed jaw. The lower jaw then returns to substantially horizontal position, whereupon the machine is in position to permit the next upper and stiffener to be placed 45 between the jaws by the operator.

For a more complete understanding of this invention, reference may be had to the accompanying drawings in which

Figure 1 is a side elevation of the machine, the cover for the gear box being removed. 55

Figure 2 is a top plan of the machine.

Figure 3 is a section through the machine on line 3—3 of Figure 1.

Figures 4, 5 and 6 are detail sections on lines 4—4, 5—5 and 6—6, respectively, of 60 Figure 1.

Figure 7 is a front elevation of the machine.

The machine comprises a supporting frame 65 consisting of a gear box 1 having a supporting base 2, one side of the gear box being open but normally closed by means of a cover 3. Journaled in the upper portion of the gear box and extending lengthwise thereof is a shaft 5 having a worm 6 thereon positioned between spaced bearings 7 and 8 which may, if desired, be formed integral with the gear box. This worm 6 meshes with a worm gear 10 journaled on a stub shaft 11 extending through the side wall 12 of the gear box and fixed in position by any suitable means as by a nut 13 threaded on its eccentrically arranged end which projects through the wall 12. This worm gear extends into the lower portion of the gear box beneath the upper edge of the wall portion 14 with which the cover 3 engages thus to provide an oil pocket within which the gear dips in order that oil may be carried thereby to lubricate the moving parts within the gear box. 70

The worm gear 10 has a laterally extended hub 15 on which is keyed a cam 16. Cooperating with this cam is a cam roller 17 journaled on a stub shaft 18 fixed to a lever arm 19. This arm 19 is fulcrumed at 20, preferably on an eccentric shaft so that its pivotal position may be adjusted by rotation of this shaft. The arm 19 extends through a slot 25 in the forward end of the gear box and its upwardly turned outer end 26 is provided with a perforation to receive a pivot 27, this pivot being fixed in position therein as by means of a set screw 28. This pivot passes through spaced bearing lugs 29 extending downwardly from a clamping jaw 30. The end 26 has an upwardly extending lug 31 75

against which the lower face of the jaw 30 normally rests, being pressed into contact therewith by means of a coil spring 32 surrounding the pivot member 27 and having one end fixed in a slot 33 therein and the other end extending into contact with a stiffening rib 34 on the under face of the jaw 30. Above the jaw 30 is a mating jaw 40 mounted in fixed position, this jaw, as shown, being integral at its rear end with the gear box and extending over the lower jaw 30.

Adjacent to the free end of the fixed jaw 40 is mounted an assembling or work table 45, as shown this being provided with a flat upper face and a socket portion 46 therebeneath for the reception of a bracket arm 47 fixed to the lower portion of the gear box. As shown this bracket arm is formed as a rod which extends into a perforation in the gear box and is fixed therein by means of a set screw 48. The forward upwardly turned end 47 of this rod extends similarly into the socket portion 46 where it is fixed by set screws 49. The upper face of the assembly or work table is fixed at a level somewhat below that of the lower face of the fixed jaw 40 so that when the movable lower jaw 30 is spaced therefrom a convenient distance, the upper with the stiffener thereon which has been locally heated, as hereinbefore described, may be pushed by the operator rearwardly between the two jaws whereupon the lower jaw may be pushed upwardly as the cam rotates to press the upper and stiffener with the desired degree of pressure between the fixed and movable jaws. As soon as the upper and stiffener have been gripped therebetween, the operator may release hold thereon and proceed to assemble another upper and stiffener in the same manner on the table 45. The cam 16 is provided with a dwell 55 so that when the roller 17 rides thereon, the movable jaw is held up in work-clamping position, this dwell being of sufficient length to cause the pressure to be exerted for the desired length of time. As the portion 55 of the cam rides out from beneath the roller 17, the arm 19 is permitted to fall by its own and the weight of the jaw 30, thus permitting the lower jaw to fall away from the upper jaw to release the work. As it continues to drop provision is made for tilting the lower jaw against the tension of the spring 32 in order that the assembled upper and stiffener may fall clear therefrom and at the same time, if desired, the work may be positively pushed away from the upper fixed jaw so as to drop freely from the machine at the completion of the pressing operation.

The tilting of the lower jaw is accomplished by means of a finger lever 60 which is pivoted on a post 61 extending forwardly from the gear box beneath the fixed jaw 40. This finger 60 has an upwardly projecting portion 62 against which the movable jaw

30 impinges as it falls away from the fixed jaw, the impingement taking place at one side of the axis of its pivotal connection with the arm portion 26. Continued downward motion of the movable jaw, therefore, causes it to be rocked about its pivot, the arm 60 also turning about its own pivot as the downward motion of the movable jaw continues until the parts reach the position shown in dotted lines in Figure 4. At the same time the work may be freed from the upper clamping jaw by means of stripper pins 70. These stripper pins ride in suitable perforations through the clamping portion of the upper jaw and are normally held raised above the lower face thereof by means such as leaf springs 71, each fixed at one end to the upper face of the platen portion 72 of the fixed jaw 40 and having a slotted end 73 extending under the head 74 at the upper end of the stripper pin. Riding on the heads of these pins is a plunger plate 75 positioned within an opening 76 in a web 77 forming part of the fixed jaw. This plate 75 is fixed to the lower end of a rod 80 which is slidable through an opening 81 in the jaw member 40, the upper end of this rod being bent rearwardly and resting in a groove in the upper face of a lug 83 projecting from the upper face of the gear box. This rod 80 has extending thereover a yoke member 84 having downwardly extending legs 85 and 86. The leg 86 is merely guided for vertical movement through a guide opening 87 in the upper face of the gear box while the leg 85 extends into the gear box through a similar opening 88 and its lower end is seated in a depression 89 in the upper face of the arm 19. Surrounding this leg 85 is a coil spring 90 which reacts between the upper wall of the gear box and a collar 92 fixed to the leg 85 by which means the yoke member 84 is urged downwardly as far as is permitted by the engagement of the lower end of the leg 85 on the arm 19. As the arm 19 swings downwardly permitting the movable jaw 30 to move downwardly and causing it to tilt, the yoke 84 is also permitted to move downwardly, the spring 90 causing it to engage above the rod 80, depressing the same and causing the stripper pins to be projected through the lower face of the fixed jaw member 40. By this means the work is detached from the upper jaw member so that it may fall freely from the machine. Adjustable stop screws 95 threaded through the upper portion of the fixed jaw 40 may be used to limit the upward movement of the block 75.

The pressed work having thus been removed from the machine, a higher portion 98 of the cam comes beneath the cam roller, causing the arm 19 to be raised sufficiently to permit the lower movable jaw to approach the upper fixed jaw and to again resume its horizontal position, the weight of the lever 60 then

returning it to the position shown in solid lines in Figure 4 in which its lower end engages a stop pin 100. As soon as this position has been reached by the lower jaw member another dwell portion 99 of the cam comes into cooperative relation with the cam roll, thus permitting this jaw to remain in this position a sufficient length of time for the operator to push the upper and stiffener assembled on the 5 plate 45 between the jaw members. At the end of the dwell the cam acts to raise the cam follower 19 to effect the pressing of the upper and stiffener together as has been heretofore described, the cycle of operations being automatically repeated as long as the machine is running. It is intended that the machine should run continuously while in operation, the operator pushing the upper and stiffener previously assembled on the table 10 45 as shown in dotted lines in Figure 2 between the jaws during the dwell when the movable jaw is positioned spaced from the upper jaw, but with its upper face substantially horizontal. As soon as the jaw has been moved upwardly to clamp the parts, the 15 operator pays no more attention to the work but starts the assembling of another upper and stiffener which may be completed by the time the work pressed between the jaws has 20 been pressed and removed and the movable jaw has resumed its position ready for the insertion of the next upper and stiffener. As shown, therefore, the shaft 5 is driven by a belt pulley 105 which may have a fly wheel 25 portion 106 this belt pulley being clutched to the shaft by means of a clutch 107 slidably axially of the shaft, but keyed thereto by the key 108, this clutch being shifted into and out of clutching position along the shaft by 30 means of a shipper 109 carried by a reciprocating shaft 110 mounted in bearings 111 extending outwardly from the cover 3. This rod 110 is readily accessible to the operator who may start and stop the machine as desired, though as above stated in the normal 35 operation the machine runs continuously.

By turning the stub shaft 11 and the fulcrum shaft 20, the extent of closing movement of the jaws may be regulated according 40 to the thickness of the material and the desired pressure.

Having thus described an embodiment of this invention, it should be evident to those skilled in the art that various changes and modifications might be made therein without departing from its spirit or scope as defined 45 by the appended claims.

I claim:

1. A machine of the class described comprising a pair of jaws between which work may be clamped, means for moving said jaws relatively toward each other to clamp work therebetween and for then separating said jaws, means for turning one of said jaws 50 during such separation to permit the work to

fall therefrom, and means for detaching the work from the other of said jaws.

2. A machine of the class described comprising a pair of jaws between which work may be clamped, means for moving said jaws relatively toward each other to clamp work therebetween and for then separating said jaws, means for turning one of said jaws during such separation to permit the work to fall therefrom, and means acting independently of said other jaw for returning the turned jaw to its former position as said jaws move relatively toward each other. 70

3. A machine of the class described comprising a pair of jaws between which work may be clamped, means for moving said jaws relatively toward each other to clamp work therebetween and for then separating said jaws, means for turning one of said jaws during such separation to permit the work to fall therefrom, means for detaching the work from the other of said jaws, and means for returning said one jaw to its former position as said jaws move relatively toward each other. 75

4. A machine of the class described comprising a fixed jaw, a jaw movable toward and from said fixed jaw, an arm to which said movable jaw is pivoted, means for moving said arm to move said jaw, and means acting positively on the movement of said movable jaw from said fixed jaw for tilting said movable jaw on its pivot. 90

5. A machine of the class described comprising a fixed jaw, a jaw movable toward and from said fixed jaw, an arm to which said movable jaw is pivoted, means for moving said arm to move said movable jaw, a stop on said arm, means tending to hold said movable jaw in contact with said stop, and a finger positioned adjacent to the path of movement of said movable jaw and against which said movable jaw impinges eccentric to its pivot as said movable jaw moves from said fixed jaw to cause said movable jaw to tilt out of contact with said stop. 100

6. A machine of the class described comprising a fixed jaw, a jaw movable toward and from said fixed jaw, a lever arm carrying said movable jaw, an adjustable fulcrum for said lever arm, a shaft having an angularly adjustable eccentric bearing portion, a cam rotatable on said bearing portion, a cam follower fixed to said lever arm, and means for rotating said cam. 115

7. A machine of the class described comprising a fixed jaw, a movable jaw, pins carried by said fixed jaw and projectable beyond the work-engaging face thereof, means for resiliently holding said pins retracted, means for moving said movable jaw toward and from said fixed jaw, and means actuated by the movement of said movable jaw from said fixed jaw for projecting said pins. 125

8. A machine of the class described, com- 130

- prising a fixed jaw, a jaw reciprocatory toward and from said fixed jaw, an arm to which said movable jaw is pivoted, means for moving said arm to move said jaw, means 5 acting on the movement of said movable jaw from said fixed jaw for tilting the movable jaw on its pivot, and means acting on the movement of said arm for stripping the work from said fixed jaw.
10. A machine of the class described, comprising an upper jaw, a lower jaw for receiving work reciprocating into and out of clamping engagement with the upper jaw, means for tilting the lower jaw to permit the work 15 to fall therefrom while it moves out of clamping engagement with said upper jaw, means for restoring said lower jaw to non-tilting position as it moves into clamping engagement with said upper jaw, and means for reciprocating said lower jaw acting to cause 20 dwells in the motion of said jaw when it is in non-tilting, work-receiving position and in work-clamping position.
11. A machine of the class described, comprising a fixed upper jaw and a movable lower jaw between which the work may be pressed, mechanism for moving the lower jaw toward and from the upper jaw, means for effecting the automatic lateral tilting of the 25 lower jaw, and means operating through the upper jaw for automatically disengaging the work therefrom.
12. A machine of the class described, comprising a fixed jaw and a movable, non-yielding lower jaw between which the work may be pressed, mechanism for moving the lower jaw about an axis toward and from the work, and means for moving said lower jaw about an axis transverse to this first-mentioned axis.
13. A machine of the class described, comprising a fixed jaw and a movable, non-yielding lower jaw between which the work may be pressed, mechanism for moving the lower jaw about an axis toward and from the work, and means for varying the limits of the path 40 of movement of said movable jaw in relation to the fixed jaw, to compensate for work of different thicknesses or to vary the pressure thereon.
50. In testimony whereof I have affixed my signature.

WILLIAM H. BAYNARD.
